**COMBINATION ROTARY MOWER HOUSING WITH
DISCHARGE DEFLECTOR AND BAG CHUTE****Richard A. Thorud, Minneapolis, Minn., assignor to Toro
Manufacturing Corporation, Minneapolis, Minn.**

Filed Jan. 14, 1971, Ser. No. 106,618

Term of patent 14 years

Int. Cl. D15—03, 99

U.S. Cl. D40—1 B

FIG. 2

FIG. 1

FIG. 3

FIG. 5

FIG. 4

FIG. 6

FIG. 1 is a top plan view of a combination rotary mower housing with discharge deflector and bag chute embodying my new design;

FIG. 2 is a side elevational view as viewed from the top side of FIG. 1;

FIG. 3 is a side elevational view as viewed from the bottom side of FIG. 1;

FIG. 4 is a bottom plan view thereof;

FIG. 5 is an end elevational view thereof as viewed from the left end of FIG. 1; and

FIG. 6 is an end elevational view thereof as viewed from the right end of FIG. 1.

I claim:

The ornamental design for a combination rotary mower housing with discharge deflector and bag chute, substantially as shown.
